US00D640270S

(12) **United States Design Patent**
Barnett et al.

(10) **Patent No.:** **US D640,270 S**
(45) **Date of Patent:** **** Jun. 21, 2011**

(54) **DISPLAY SCREEN WITH USER INTERFACE**

(75) Inventors: **Don Barnett**, Monroe, WA (US); **Jeffrey C. Fong**, Seattle, WA (US)

(73) Assignee: **Microsoft Corporation**, Redmond, WA (US)

(**) Term: **14 Years**

(21) Appl. No.: **29/364,501**

(22) Filed: **Jun. 24, 2010**

(51) **LOC (9) Cl.** 32-00

(52) **U.S. Cl.** **D14/487**

(58) **Field of Classification Search** D14/485-495; 715/700-867

See application file for complete search history.

(57) **CLAIM**

The ornamental design for a display screen with user interface, as shown and described.

DESCRIPTION

FIG. 1 is a front view of a display screen with user interface showing our new design; and, FIG. 2 is a front view of display screen with user interface of FIG. 1 shown on a device.

The broken line showing of the remainder of the display screen in FIGS. 1-2, and the device in FIG. 2 illustrates unclaimed environment and forms no part of the claimed design.

1 Claim, 2 Drawing Sheets

FIG. 1

FIG. 2
